UNITED STATES PATENT OFFICE.

JOHN H. WHITAKER, OF DAVENPORT, IOWA.

AUTOMATICALLY-OPERATING DOOR.

SPECIFICATION forming part of Letters Patent No. 628,885, dated April 29, 1902.
Application filed February 5, 1901. Serial No. 46,070. (No model.)

To all whom it may concern:

Be it known that I, JOHN H. WHITAKER, a citizen of the United States of America, and a resident of Davenport, in the county of Scott and State of Iowa, have invented certain new and useful Improvements in Automatically-Operating Doors; and I do declare the following specification, taken in connection with the drawings making a part of the same, to be a full, clear, and exact description thereof.

This invention relates to devices for operating doors automatically, and is especially useful when connected with a door between dining-room and kitchen, where the advantage of being able to open a door without using the hands will be apparent.

The object of this invention is to cause a door to which my device is attached to be opened automatically when a plate slightly elevated above the floor and operatively connected with mechanism located below the floor is depressed, thus enabling a person to pass through such doorway and to cause such opened door to close automatically when the person has passed through the doorway and when the pressure on the plate has been released.

A further object is to simplify and improve the mechanism shown and described in my previous patents of record.

Figure 1 is a front elevation of a door to which my invention is connected and attached. Fig. 2 is an enlarged detail view of the tread-button or plate mechanism from the side indicated by the arrow in Fig. 1. Fig. 3 shows about the angle of the connecting-lever with reference to the tread-button and the vertical engaging rod, hereinafter described.

In the drawings, 1 represents the floor-line. 2 is the door, which has secured to its top by suitable brackets the rollers 3. These rollers are mounted to run upon the rail 4.

To the rear edge of the door I secure an oil-chamber, in which is placed a piston-rod having a plunger at its lower end, which in the operation of my invention serves as a cushion to avoid sudden jarring when the door reaches its open or closed position and to retard the movement of the door when near its open or closed position. An angular weighted arm 5, pivoted to a brace secured to the wall or

otherwise, and an upper arm operatively connecting the pivoted arm with the piston-rod in the cylinder are used in this improvement; 55 but as these parts are in all respects substantially the same as shown and described in my Patent No. 632,299, September 5, 1899, to which reference is made, a further description thereof will be unnecessary. 60

5^a represents a short arm which extends inwardly at right angles from the angular arm 5 at a point adjacent to where it is pivoted to the brace and is preferably made integral with the arm 5. 65

6 is a vertical rod, its upper end adapted to be loosely connected with the end of the projecting arm 5 and passing through the floor 1. 7 is a lever-arm located underneath the floor and having its fulcrum in a bearing 7^a 8, which may be secured to a block 9 or in any other suitable manner just underneath the floor. One end of such lever-arm is loosely connected with the lower end of the vertical rod 6, and it extends from that connection to a point which is vertically below the end of the post 10. 75

11 represents the guide-plate, which is let into the floor so that the top of the floor is flush with the top of said plate. Said plate 80 is provided with two downwardly-projecting ears 11^a and 11^b, notched to receive the hooks 12^a and 12^b of the connecting-plate 12. Said connecting-plate 12 consists of a flat rectangular plate with a central opening and provided with 85 four hooks, one at each corner, (designated by 12^a, 12^b, 12^c, and 12^d,) the last-named hook not being shown in the drawings. The tread-button 13 is movable vertically in the guide-plate 11 and may be provided with pieces of 90 rubber 13^a and 13^b, secured in the face or top of such button. Projecting downwardly from the tread-button 13 at two of its corners and opposite to the ears 11^a and 11^b are two similar notched ears, one of which is shown in 95 Fig. 2, (marked 13^c), and the hooks 12^c and 12^d of the hinge-plate 12 rest in such notches.

Projecting downwardly from the center of the under side of the tread-button 13 is a socket 13^e, which receives the upper end of 100 the post 10. It will be seen that by this form of tread-button mechanism the place of contact with the tread-button is immaterial to its successful operation. The plate being con-

nected with both the tread-button and the guide-plate will prevent binding and friction between the parts.

By stepping upon the tread-button at any point it will be depressed in a true vertical line, and the post 10 being connected with one end of the fulcrumed lever-arm 7 will cause the other end thereof to be raised. This will elevate the vertical rod 6 and through its connection with the short arm 5^a of the angular pivoted arm 5 said angular arm will swing on its pivot. This will draw the door 2 backward and open. When the pressure has been released from the tread-button 13, the weight 15 at the bottom of the angular arm 5 will cause said arm to swing back to its normal position, and this action will close the door.

Having thus described my invention, I claim as new and desire to secure by Letters 20 Patent—

1. In an automatically-operating door, the combination of a door, a horizontal rail, means for suspending said door from the rail, an angular pivoted arm composed of three members, its upper member loosely connected with the rear of the door, its lower member provided with a weight, its third and shorter member extending inwardly at right angles to the upper member, a vertical rod whose 25 upper end is loosely connected with said shorter member, said rod extending through and some distance below the floor, a lever-arm supported and fulcrumed in a bearing underneath the floor, one end of said lever-arm loosely connected 30 with the lower end of the vertical rod, an upright post to whose lower end the other end of the lever-arm is loosely connected, a guide-plate having two downwardly-projecting notched ears, a tread-button adapted to move 35 vertically in said guide-plate and provided with similar notched ears, a connecting-plate with four hook-shaped corners, such hooks adapted to rest in the notched ears of the guide-plate and tread-button; the tread-button provided with a central socket on its under side to receive the upper end of the upright post for the purposes stated and substantially as described.

2. In an automatically-operating door, the combination of a horizontal rail, a door mounted thereon, guide-rods secured to the rear 40 purposes stated.

2. In an automatically-operating door, the combination of a horizontal rail, a door mounted thereon, guide-rods secured to the rear

edge of the door, a roller between said guide-rods, an angular pivoted arm composed of 45 three members, its lower member provided with a weight, its upper member connected with the roller, its third and shorter member extending at right angles to the upper member, a vertical rod whose upper end is loosely 50 connected with said shorter member, said rod extending through and some distance below the floor, a lever-arm supported and fulcrumed in a bearing underneath the floor, one end of said lever-arm loosely connected 55 with the lower end of the vertical rod, an upright post to whose lower end the other end of the lever-arm is loosely connected, a guide-plate having two downwardly-projecting notched ears, a tread-button adapted to move 60 vertically in said guide-plate and provided with similar notched ears, a connecting-plate with four hook-shaped corners, such hooks adapted to rest in the notched ears of the guide-plate and tread-button; the tread-button provided with a central socket on its under side to receive the upper end of the upright post for the purposes stated and substantially as described.

3. A tread-button having a central socket 70 on its under side and provided at one edge with two downwardly-projecting notched ears, a guide-plate surrounding said tread-button and provided with two similar notched ears on the side opposite the notched ears of 75 the tread-button, a connecting-plate having a central opening and provided with four hooks to engage and operatively connect the notched ears of the tread-button and guide-plate, substantially as described.

In witness whereof I have hereunto set my hand this 26th day of January, A. D. 1901.

JOHN H. WHITAKER.

In presence of—

I. C. ANDERSON,
C. F. HOLMES.
